UNITED STATES PATENT OFFICE

153,495

DESIGN FOR A SOLDERING GUN

Joseph L. Caliri, Orange, N. J.

Application October 18, 1948, Serial No. 149,174

Term of patent 3½ years

(Cl. D26—1)

To all whom it may concern:

Be it known that I, Joseph L. Caliri, a citizen of the United States, residing at Orange, in the county of Essex and State of New Jersey, have invented a new, original, and ornamental Design for a Soldering Gun, of which the following is a specification, reference being had to the accompanying drawing, forming part thereof.

Figure 1 is a rear perspective view of a soldering gun, showing my new design, and

Figure 2 is a front perspective view thereof.

I claim:

The ornamental design for a soldering gun, as shown.

JOSEPH L. CALIRI.
